UNITED STATES PATENT OFFICE.

JOHN J. NASH, OF WATERBURY, CONNECTICUT, ASSIGNOR TO AMERICAN PIN COMPANY,
OF WATERBURY, CONNECTICUT.

DESIGN FOR A BEDSTEAD-TRIMMING.

47,856.

Specification for Design.

Patented Sept. 21, 1915.

Application filed November 10, 1914. Serial No. 871,411. Term of patent 7 years.

To all whom it may concern:

Be it known that I, JOHN J. NASH, a citizen of the United States, residing at Waterbury, in the county of New Haven and State of Connecticut, have invented a new, original, and ornamental Design for Bedstead-Trimming, of which the following is a specification, reference being had to the accompanying drawing, forming part thereof.

In the drawings, Figure 1 is a plan view

of a bedstead trimming showing my design; Fig. 2 is a view in elevation of the same.

I claim:

The ornamental design for a bedstead trimming, as shown.

JOHN J. NASH.
